[57] CLAIM

The ornamental design for the knife handle, as shown
and described.

DESCRIPTION

FIG. 1 is a perspective view of a knife handle showing
my new design;

FIG. 2 is a top plan view thereof;

FIG. 3 is a right side elevational view thereof, the left
side elevational view being a mirror image thereof;

FIG. 4 is a rear elevational view thereof;

FIG. 5 is a front elevational view thereof; and,

FIG. 6 is a bottom plan view thereof.

The broken line showing of a knife blade in FIGS. 1-3,
5 and 6 is environmental only and forms no part of the
claimed design.
